The dominant features of my design reside in those portions shown in full solid lines.

I claim:

The ornamental design for a pull for furniture or the like, substantially as shown and described.
